Inventor:

Milton Tibbets.

UNITED STATES PATENT OFFICE.

MILTON TIBBETTS, OF DETROIT, MICHIGAN, ASSIGNOR, BY MESNE ASSIGNMENTS, TO
THE ISKO COMPANY, OF CHICAGO, ILLINOIS, A CORPORATION OF DELAWARE.

REFRIGERATING APPARATUS.

1,276,450.

Specification of Letters Patent. Patented Aug. 20, 1918.

Application filed July 28, 1916. Serial No. 111,832.

To all whom it may concern:

Be it known that I, MILTON TIBBETTS, a citizen of the United States, and resident of Detroit, Wayne county, State of Michigan, 5 have invented certain new and useful Improvements in Refrigerating Apparatus, of which the following is a specification.

This invention relates to refrigerating apparatus, and particularly to refrigerating 10 apparatus of the compression type.

One of the objects of the invention is to provide an improved form of expansion coil.

Another object of the invention is to provide an expansion coil in which the ice making loops have a direct lead from the condenser to thus use the most effective loops 15 of the coil for ice making.

Other objects of the invention will appear 20 from the following description taken in connection with the drawings which form a part hereof, and in which:

Figure 1 is a front elevation and part 25 section of a refrigerating apparatus embodying this invention, and

Fig. 2 is an elevation view of a slightly 30 different form of expansion coil from that shown in Fig. 1.

Referring to the drawings, 10 represents 35 a refrigerator of usual form, having a refrigerating compartment 11 and food compartments 12. A compressor 13 is mounted on the refrigerator and is driven by a suitable electric motor 14 as by a belt 15.

35 A condenser 16 shown somewhat diagrammatically is connected at one end to the compressor and at the other end to an expansion valve 17 of any desired construction. The valve 17 is shown inside the refrigerator 40 compartment 11. A short pipe 18 leads from the inlet side of the compressor to the top of the compartment 11 adjacent the valve 17.

An expansion or refrigerating coil 19 is 45 arranged in the compartment 11, and in the illustrative form of the invention shown in Fig. 1, this coil has its inlet and outlet ends arranged at the top of said compartment, the inlet end 20 being connected to the valve 50 17 at the outlet end of the condenser 16, and the outlet end 21 being connected to the inlet end of the pipe 18, and it comprises a vertical pipe 22 leading from the inlet end 20 of the coil directly to the lower part of 55 the compartment 11, a pipe 23 including sev-

eral loops forming an inclosure 24 for an ice making pan 25, and a pipe 26 including several loops extending upwardly from one of the loops of the pipe 23 to the outlet end 21 of the coil.

It will be understood that a suitable refrigerant, such as sulfurous acid (SO_2) is used and, being compressed by the compressor 13, it is passed through the cooler or condenser 16 and expanded through the 60 valve 17 into the coil 19. It returns to the compressor through the pipe 18. Thus the coldest parts of the coil 19 are the pipes 22 and 23, the pipe 26 getting relatively warmer as the top of the coil is reached. By this 65 arrangement of the coil 19 water in the pan 25 is more quickly formed into ice than when the coil is looped from the top downwardly, and the air circulating through the coil, from the top toward the bottom of course, 70 strikes the relatively warmer pipe first and the coldest pipe last, thus operating most 75 efficiently.

Should the form of refrigerant used or the size of piping employed make it difficult 80 to pump the refrigerant from the bottom of the coil indirectly through the several loops as illustrated in Fig. 1, another form of the invention may be used as illustrated in Fig. 2, in which the expansion coil 19^a comprises 85 a vertical pipe 22 and a looped pipe 23 similar to that of Fig. 1, a second vertical pipe 27 extending from one of the loops of the pipe 23 to the upper part of the compartment, a pipe 26^a including several loops ex- 90 tending from the upper to the lower part of the compartment, and a third vertical pipe 28 extending from one of the lower loops of the pipe 26^a to the outlet end of the coil. With this coil construction there is a direct 95 pull through the pipe 28 from the lowermost loop of the pipe 26^a and no trouble is experienced in raising the refrigerant. At the same time the colder part of the coil is used for ice making and the air passes over 100 the ice making loops last.

Other forms may be made without departing from the spirit or scope of this invention.

Having thus described my invention 105 what I claim and desire to secure by Letters Patent is:—

1. In a refrigerating apparatus, the combination with a compressor, and a condenser, of an expansion coil connected to said com- 110

pressor and condenser, comprising a pipe extending downwardly from its inlet end piping connected to said downwardly extending pipe and forming an inclosure for 5 an ice making pan, and a pipe formed in a plurality of loops from said piping to the outlet end of said coil.

2. In a refrigerating apparatus, the combination with a compressor, and a condenser, 10 of an expansion coil connected to said compressor and condenser, comprising a pipe extending downwardly from its inlet end piping connected to said downwardly extending pipe and forming an inclosure for 15 an ice making pan, and a pipe formed in a plurality of loops reaching upwardly from said piping to the outlet end of said coil.

3. In a refrigerating apparatus, the combination with a refrigerator having a compartment, a compressor and a condenser, of 20 a refrigerating coil in said compartment connected to said compressor and condenser and comprising piping forming an inclosure for an ice making pan, and a pipe formed 25 in a plurality of loops or sections extending from said piping to the outlet end of said coil.

4. In a refrigerating apparatus, the combination with a refrigerator having a compartment, a compressor and a condenser, of 30 a refrigerating coil in said compartment connected to said compressor and condenser and comprising piping forming an inclosure for an ice making pan, said piping being 35 arranged adjacent the bottom part of said compartment, and a pipe formed in a plurality of loops or sections extending upwardly from said piping to the outlet end of said coil.

40 5. The combination with a refrigerator having a refrigerating compartment, of a refrigerating coil entering and leaving said compartment adjacent the top thereof, said coil comprising a pipe leading from its in- 45 let to the lower part of said compartment, a plurality of loops of pipe at the bottom of said compartment forming an inclosure for an ice making pan, and a plurality of loops of pipe between said bottom loops and the 50 outlet end of said coil.

6. The combination with a refrigerator having a refrigerating compartment, of a

refrigerating coil entering and leaving said compartment adjacent the top thereof, said coil comprising a pipe leading from its inlet 55 directly to the lower part of said compartment, said pipe there forming several loops around a space for an ice making pan and then leading upwardly in the form of additional loops to the outlet end of said coil. 60

7. The combination with a refrigerator having a compartment, of a refrigerating coil in said compartment comprising a vertical pipe extending from the inlet end of 65 said coil to the lower part of said compartment, a pipe including several loops forming an inclosure for an ice making pan and a pipe including several loops extending from the lower part to the upper part of said compartment. 70

8. The combination with a refrigerator having a compartment, of a refrigerating coil in said compartment comprising a vertical pipe extending from the inlet end of 75 said coil to the lower part of said compartment, a pipe including several loops forming an inclosure for an ice making pan, a second vertical pipe extending from one of said loops at the lower part of said compartment to the upper part thereof, a pipe 80 including several loops extending from the upper to the lower part of said compartment, and an outlet pipe from the lower end of one of the last said loops.

9. The combination with a refrigerator 85 having a compartment, of a refrigerating coil in said compartment comprising a vertical pipe extending from the inlet end of said coil to the lower part of said compartment, a pipe including several loops forming 90 an inclosure for an ice making pan, a second vertical pipe extending from one of said loops at the lower part of said compartment to the upper part thereof, a pipe including several loops extending from the 95 upper part thereof, a pipe including several loops extending from the upper to the lower part of said compartment, and a third vertical pipe extending from one of the lower said loops to the outlet end of said coil at 100 the top of the compartment.

In testimony whereof I affix my signature.

MILTON TIBBETTS.
